RECIPROCATING CYLINDER PHONOGRAPH

Irvine Siegel, New York, N. Y.

Application January 3, 1949, Serial No. 68,860

13 Claims. (Cl. 274—19)

1

The present invention relates to a phonograph and, more particularly, to a miniature phonograph which is adapted to be used in a doll or similar toy.

There have been many attempts heretofore to make a talking doll but, so far as is known, all these attempts have failed to achieve commercial success. Some proposed designs have been unsatisfactory from the standpoint of performance. Others have been so complicated that manufacture at a reasonable price was precluded.

The present invention has as an object the provision of a simple phonograph unit for use with dolls and the like which is dependable in operation, simple in construction and comparatively inexpensive to manufacture. Other objects and advantages of the invention will become apparent from the following detailed description taken in conjunction with the drawing, in which:

Fig. 1 is an elevation, partly in section, of a phonograph embodying the invention;

Fig. 2 is a fragmentary sectional elevation at right angles to Fig. 1; and

Fig. 3 is a fragmentary section on a larger scale through the drum and its shaft.

Referring now to the drawing, the phonograph unit comprises a base 1 on which is mounted a spring motor 3 for driving a record unit 5 and a housing 7 in the end of which a speaker unit 9 is mounted. The spring motor 3 has a casing 11 of circular shape in plan view flattened on one side which is partially cut away to permit a flanged gear 13 to extend outside the casing as seen in Fig. 1. This gear is rotatably mounted on a shaft 15 which extends through base 1 to form a winding key 17. The other end of shaft 15 extends above casing 11 and is threaded to form a screw 19. A spring plate 21, which is fixed to shaft 15 just below the gear 13, is provided with a plurality of peripheral teeth 23, only one of which is shown, which engage with teeth 25 formed in the lower face of gear 13 and constitute a ratchet and pawl device of conventional structure for permitting a spiral spring which has one end 27 fixed to the casing 11 and the other end to the shaft 15 to be wound up by turning the key 17 in one direction without rotating the gear 13. When the spring uncoils, it drives the gear 13 and the shaft 15 in the direction opposite to the winding motion.

Gear 13 meshes with the first gear of a gear train 29. The gears of this train drive a record shaft 31 which is journaled at one end in a wall 33 and at the other end in a removable bracket 35 both of which are suitably secured to base 1.

2

The speed of rotation of shaft 31 is limited by an air governor 37 which is mounted on a shaft 39 with a spiral gear 41 which meshes with the end gear of the train 29 as shown in Fig. 2. A stop pin 43 is mounted for limited axial movement in base 1 so that in one position its inner end is in the path of movement of the governor 37 and in the other position is clear thereof.

A drum 45 is mounted on shaft 31 for rotation therewith and for easy sliding movement therealong. While any means for accomplishing this function can be used, it is preferred to have a non-circular shaft and a correspondingly shaped opening through the drum with sufficient clearance for easy movement of the drum along the shaft but without excessive play. A satisfactory arrangement is shown in Fig. 3 in which the shaft is square with chamfered corners and the drum is first drilled and then broached accurately to size. This reduces sliding friction to a minimum while providing certain rotation of the drum with the shaft. A light helical spring 47 biases the drum toward one end of the shaft to the position shown in Fig. 1.

On the drum 45 is mounted a record cylinder 49 having a helical sound track cut or pressed into its outer surface. The record is replaceable by removing bracket 35 and slipping the record off the drum on which it is merely frictionally held through an opening 51 in the housing 7. The drum is preferably made of heavy material so that it serves as a flywheel as well as a record holder, but separate pieces may be used if desired for these two functions.

The speaker unit 9 includes a diaphragm 53, preferably of conical type, secured at its periphery to a frame or ring 55 which forms part of a spider 57 having arms extending inwardly and downwardly to a bifurcated or annular hub portion spanning a pin 59 secured to the apex of the diaphragm. To the pin 59 is fixed an arm 61 which carries a needle 63. A pair of bracket members 65 are fixed to the speaker spider and a pin 67 passes through them and the arm 61 which is drilled oversize to receive a rubber sleeve. The arm 61 is thus pivoted to the spider but with some freedom of movement due to the resiliency of the rubber sleeve. The vibrations picked up by the needle 63 from the sound track of the record are amplified somewhat by the mechanical connection between needle 63 and the diaphragm 53, but such a connection is not essential and the needle may be connected directly to the diaphragm if desired.

The speaker unit is resiliently mounted in the

housing 7 for limited axial movement between a shoulder 71 and a locking ring 73 which is screwed into the end of the housing. A resilient ring 75, which preferably is made of rubber, lies between shoulder 71 and the ring 55. A similar ring 77 lies between ring 55 and locking ring 73, preferably with a washer 79 between the rings 73 and 77 so that the ring 73 can be turned without rubbing directly on ring 77. It will be apparent that the normal position of the speaker unit relative to housing 7 can be adjusted somewhat by turning locking ring 73 and thus vary the stress on the two resilient rings 75 and 77. In this normal position the end of the needle 63 rides in the sound track of the record with the proper pressure for picking up the recorded vibrations and transmitting them to the diaphragm 53. While the parts 55, 73, 75, 77 and 79 have been described as circular, which is the simplest shape to use, they may be oval, elliptical, etc., except for the locking ring which may be replaced by other locking means capable of limited axial adjustment.

A lifting device 81 is provided for disengaging the needle from the sound track at the end of the run. The form shown in the drawing comprises a bifurcated plate 83 having a pair of arms 85 extending under the hub of spider 57, a threaded sleeve 87 engaging the screw 19 and a smooth bore sleeve 89 slidably engaging a post 91 mounted on the wall 33. The parts are so arranged that rotation of the shaft 15 during the winding of the motor spring lowers the lifting device 81 and permits the speaker unit to occupy its normal position while the reverse rotation of the shaft 15 causes the lifting device to rise.

The operating cycle begins with the parts in the position shown in Fig. 1 in which the needle 63 is raised out of the sound track and the record 49 is at the outermost position on the shaft 31 with the starting end of the sound track under the needle 63. This is the position the parts assume when the spring of motor 3 is unwound at the end of the playing run. To place the device in condition again for playing, the stop pin 43 is pushed inwardly to position its inner end in the path of the governor 37 as shown in Fig. 2. The spring is then wound up by turning the winding key 17. In so doing the shaft 15 and screw 19 turn in the direction to lower the lifting device 81 and permit the needle 63 to enter the sound track of the record 49 as shown in Fig. 2. The playing of the record is initiated by pulling the stop pin out so that it clears the governor 37, thus permitting the spring motor to drive the gear train. The governor 37 limits the speed of the record 49 and the momentum of drum 45 which is built up when the force of the motor spring is at a maximum keeps the speed of the record practically constant toward the end of the run when the force of the spring diminishes. During the run the record unit 5 is moved along the shaft 31 by the force of the needle tracking in the sound groove. At the end of the run the lifting device 81 engages the hub 57 and lifts the needle 63 from the sound track, thus freeing the record unit 5 and permitting the spring 47 to return it to the starting position of Fig. 1.

The lifting device 81 removes the needle 63 gradually from the sound track and there is a slight tendency to wear a cross groove in the record at the place where it breaks contact and the return movement of the record unit 5 under action of spring 47 begins. This has not been found to be a disadvantage in actual practice be-

cause the last turn or so of the sound track is left blank. If desired, however, a lifting device which lifts the needle suddenly can be employed. One such device may comprise a lever pivoted at one end to a post on wall 33 with the other end adapted to engage either the hub of spider 57 or the arm 61 between pivot 67 and needle 63. A stop is provided to limit the downward movement of the lever. A helical spring is secured at one end to the lever intermediate the ends thereof and the other end of the spring is connected to a threaded sleeve similar to 87. The parts are arranged so that at the end of the run the point of connection of the spring to the threaded sleeve just passes the projection of a line through the fulcrum of the lever and the point of connection of the spring to the lever. This causes the lever to snap upwardly by toggle action and lift the needle suddenly. The reverse action takes place on winding the spring motor when the threaded sleeve is lowered so that the point of connection of the helical spring therewith moves to the other side of said projected line and snaps the lever downwardly against its stop.

If the phonograph unit is used in a stuffed doll, the housing must be dust proof or otherwise protected against entrance of stuffing into the mechanism. One simple way to make the device airtight is to construct the bracket 35 in the form of a removable cover for opening 51.

Although the invention has been described and illustrated in connection with the best embodiment known at this time, modifications and variations of parts and their arrangements can be made without departing from the spirit of the invention and the scope of the appended claims.

I claim:

1. A phonograph comprising a spring motor including a gear train, said spring motor including a shaft having a winding key at one end and a screw thread at the other, a record shaft driven by said spring motor, a record unit including a cylindrical record with a helical sound track mounted on said record shaft for rotation therewith and movement therewith, a speaker unit including a needle adapted in one position to engage in the sound track of the record and in another position to be clear thereof, said record being moved along said shaft during rotation thereof by the engagement of the needle in the sound track, and lifting means for moving the needle into and out of engagement with the record operatively connected with said screw thread.

2. A phonograph as set forth in claim 1 in which a helical spring is provided around the record shaft to return the record unit to the starting position when the needle is lifted clear of the sound track.

3. A phonograph comprising a spring motor including shaft and a gear train, an air governor for said gear train, a record shaft driven by said motor, a record unit including a record having a sound track mounted on said record shaft, a fly-wheel operatively connected with said gear train, a speaker unit including a needle, and means for moving the needle into and out of engagement with the record, said means including threads on the spring motor shaft and a threaded sleeve engaged therewith and operatively connected with the needle.

4. A phonograph comprising a housing, a record unit including a spring motor and a cylindrical record having a helical sound track mounted in said housing, a conical diaphragm, a ring secured directly to the periphery of said diaphragm,

said ring being resiliently secured in said housing for limited movement axially thereof, a needle connected to the apex of said diaphragm, said needle being adapted in normal position to engage in said sound track, and means for lifting the needle from the sound track by moving said ring.

5. In a phonograph having a tubular housing; a record unit mounted in one end of said housing and a speaker unit mounted in the other end of said housing; said speaker unit comprising a diaphragm, a needle connected to said diaphragm, and an open annular frame secured directly to the periphery of said diaphragm, said frame having an outer diameter only slightly smaller than the internal diameter of said housing and being resiliently connected with said housing for limited axial movement whereby said needle can be moved toward and away from said record unit.

6. A phonograph as set forth in claim 5 in which the resilient connection comprises rubber rings on each side of said annular frame and means are provided for varying the stress on said rubber rings to adjust the normal playing position of said needle.

7. A phonograph as set forth in claim 5 in which said frame is a spider having a hub adjacent to said needle and means for engaging said hub to lift the speaker unit and free the needle from engagement with the record.

8. A phonograph as set forth in claim 7 in which said means is a member capable at least in part of axial movement which engages said hub and lifts the needle from said record unit at the end of the playing cycle.

9. A phonograph as set forth in claim 8 in which said record unit includes a spring motor

having a shaft with a winding key on one end and a screw thread on the other, said screw thread being operatively connected with said member.

10. A phonograph as set forth in claim 9 in which said record unit includes a record shaft, a drum mounted for rotation with and sliding movement along said record shaft, a cylindrical record on said drum, and a helical spring for returning the drum to its initial position on said shaft after the needle is disengaged from the record.

11. A phonograph as set forth in claim 10 in which said drum is made of a heavy material and serves as a flywheel.

12. A phonograph as set forth in claim 11 in which the spring motor for driving the record unit is connected through a gear train with an air governor.

13. A phonograph as set forth in claim 12 in which a stop pin is slidably mounted in said housing for movement into and out of the path of said air governor.
